COTTON TREATING MACHINE

Filed Feb. 15, 1932

INVENTOR:
JOHN E. MITCHELL.

BY Bruce S. Elliott

ATTORNEY.

UNITED STATES PATENT OFFICE

JOHN E. MITCHELL, OF DALLAS, TEXAS

COTTON TREATING MACHINE

Application filed February 15, 1932. Serial No. 592,866.

This invention relates to an improved construction of cotton treating machines adapted to be positioned on top of a gin stand, and has for its general object to provide such a machine with a removable supporting section having mounted thereon certain of the operating parts of the machine, whereby said supporting section with the operating parts mounted therein may be removed at will to enable access to be had to the interior of the gin stand for the purpose of making renewals, adjustments, repairs, etc.

As indicated above, it is customary to mount cleaner feeder and cotton extracting machines directly on top of gin stands, but when the space above the gin is utilized for installing cleaning and extracting mechanism, and mechanical means for collecting or removing the trash separated, access is then prevented to the brush doffers and other parts of the gin. In other words, it becomes necessary to dismount or entirely remove such machinery from the top of the gin stands in order to give access to the brush doffers of brush gins, and to other parts of the gin, which at times require inspection or repair.

To obviate this difficulty, and at the same time utilize the available space above each gin for cleaning and extracting mechanism, I have provided a removable supporting section for the lower portion of such cleaning or extracting machine, and mount certain operating parts unitary with the removable or detachable section, so that when the section is removed, ample space is provided for giving access to the brush doffers or other parts of gins, without disturbing the main body of the machine mounted thereon.

The invention is illustrated in the accompanying drawing, in which:—

Figure 1 is a longitudinal sectional view showing a simple cleaner feeder machine mounted on a gin stand, a portion only of the upper portion of the latter being shown; and

Figure 2 is a cross sectional view through the detachable unit taken on the line 2—2 of Figure 1.

Referring now to the drawing, the numeral 1 indicates a gin stand in which is mounted the upper brush doffer 2 rotating adjacent

the breast 3 of the gin. Mounted on top of the gin stand 1 is, in this instance, a cleaner feeder machine indicated, generally, by the numeral 4, said machine comprising a pair of feeding rolls, 5, for regulating the stream of cotton withdrawn from the hopper and fed into the machine, and a series of beating cylinders, 6, for agitating the cotton over screen surfaces, 7, before it is discharged from a spout, 8, into the breast 3 of the gin.

A more detailed description of the machine 4 is not required for the purposes of this case, as said machine is only illustrative of a type of machine that in practice is mounted on the gin stand. In other installations, a cotton cleaning or extracting machine might be mounted on the gin stand where I have shown a cleaner feeder machine to be mounted.

In either type of machine, the major portion of the housing usually is formed of sheet metal, as indicated at 8a, and in the preferred embodiment of the invention, the bottom of this housing is shaped to provide an inclined wall, 9, leading to a trash outlet, 10, below which is a conveyor, 11, for conducting trash from the machine. The machine 4, as a whole, is supported on the gin stand by means of rear supporting members, 11a, and front supporting members, 12. The rear supporting members 11a are rigidly connected to the bottom of the machine at each corner thereof and are secured together by means of a rod, 13, extending through a spacing tube, 14, which extends between the two supports 11 and abuts against the inner side of each, in a manner well understood.

The front supporting members 12 are formed as a unitary part of a removable section, and each support includes a portion of the side wall of the machine, which portion is indicated by the numeral 15. Extending between the two supporting members 12 is a curved housing section, 16, on each end of which is secured a flange, 17, by means of which each end of the housing section may be bolted, riveted, or otherwise secured to the side members 15 of the movable section, as indicated at 18. The housing section 16 not only serves as one of the means for hold-

ing the two front supporting members 12 together, but it also operates to catch trash discharged through the screen 7 located above it in the main body of the machine. In like manner, if an extracting machine were mounted on the gin stand, the housing section would receive trash discharged from the extracting mechanism. The supporting members 12 are additionally secured together by means of a rod, 19, passing through a spacing tube 20, which extends the full length of the machine, from one of the supports to the other.

The spout 8, previously referred to, is adjustably mounted in the removable front supporting section by being secured to a shaft 21, which is mounted in bearings (not shown) carried by the two side members 15 of the front supporting members. The numeral 22 indicates a trash sweep, which is secured to, and adapted to be rotated by a shaft 23, mounted in bearings (not shown) also carried by the side members 15 of the front supporting members. The upper end of the housing section 16 is adapted to abut against the bottom of an inner casing section 24, and the lower edge of said housing section is similarly adapted to abut against the lower edge of an upwardly inclined part of the housing 8a to provide a continuation of the wall of the trash receptacle formed by the housing section 16.

The casing section 24 forms with the front wall of the housing 8a an outlet 25 for the cleaned cotton located immediately above the spout 8.

In order to secure the detachable front supporting section to the main body of the machine, said section is provided at each side at its top and rear with flanges, 26, and is adapted to be secured to similar flanges, 27, formed on the walls of the main body of the machine, by means of bolts, 28.

From an inspection of Figure 1, it will be readily seen that with the machine 4 mounted on the gin stand, and in the absence of my invention, it would be impossible to gain access to the brush doffer 2, or to any other working part of the gin located under said machine, without dismounting the latter, or removing it in its entirety from its position on the gin.

According to my invention, the necessity of removing the machine 4, to permit access to the interior of the gin is entirely obviated. By simply removing the bolts 28, the entire front supporting section, together with the sweep 22 and spout 8, may be removed, providing a wide, open space, which gives free access to the brush doffer and other parts of the gin below. This removable section may be as readily connected to the main body of the machine by restoring the parts to the position shown in Figure 1, and then securing the bolts 28 in the flanges 26 and 27.

When the front supporting section is removed, the machine may be temporarily supported at the front by a rope or chain suspended from above.

The sweep 22 is the preferably form of mechanical means for handling the trash separated in the front part of the machine, for the reason that it is necessary to have the trash conveyor 11 in the rear of the machine, and by merely sweeping the trash out of the housing section 15 to the inclined wall 9 over which it slides into the conveyor 11, I avoid the necessity of an additional conveyor. However, it is obvious that other means than the sweep could be mounted in the detachable section for removing the trash.

I claim:

1. In a machine for treating cotton designed to be positioned on top of a gin stand, a removable section forming a support for the machine and having parts of the operating elements of the machine mounted therein, whereby when said section is removed a space will be provided to permit access to the interior of the gin.

2. In a machine for treating cotton designed to be positioned on top of a gin stand, in combination with a main housing inclosing, in part, the cotton treating mechanism, a removable section forming a support for the machine, having parts of the operating elements of the machine mounted therein and carrying a housing section unitary therewith forming a continuation of the wall of said main housing, whereby when said section is removed a space will be provided to permit access to the interior of the gin.

3. In a machine for treating cotton designed to be positioned on top of a gin stand, in combination with a main housing inclosing, in part, the cotton treating mechanism, a removable section forming a support for the machine and having parts of the operating elements mounted therein, a housing section carried by said removable section and providing, when the section is in place, a trash receptacle the wall whereof constitutes a continuation of the wall of said main housing, a trash remover mounted in said removable section and adapted, in operation, to remove trash from said receptacle, whereby, when said section is removed, a space will be provided to permit access to the interior of the gin.

4. In a machine for treating cotton designed to be positioned on top of a gin stand, in combination with a main housing inclosing, in part, the cotton treating mechanism, a support for said machine comprising side members, a housing section connecting the two side members and forming, when the support is in position a continuation of the wall of said main housing, and an operating element of the machine, normally located in the lower part thereof, mounted in said side

members, said side members, housing section and operating element being constructed as a unitary section removable from the main body of the machine, and which, when removed, provides a space permitting access to the interior of the machine.

5. In a machine for treating cotton designed to be positioned on top of a gin stand, in combination with a main housing inclosing, in part, the cotton treating mechanism, a pair of side supporting members for said machine, a housing section connecting said side members and forming a continuation of the wall of the main housing, said housing 10 section being shaped to provide a trash receptacle, a trash remover mounted in said side members and cooperating with said trash receptacle, said side members, housing section and trash remover providing a unitary section of the machine, and means for detachably connecting said section to the main body of the machine, whereby it may be removed at will to provide a space giving access to the interior of the gin.

25. 6. In a machine for treating cotton designed to be positioned on top of a gin stand, in combination with a main housing inclosing, in part, the cotton treating mechanism,

a removable front section forming a support for the machine, having parts of the operating elements of the machine mounted therein and carrying a cotton discharge spout, and a housing section formed as a unitary part of 70 said removable section and constituting a continuation of the wall of the said main housing, whereby when said section is removed a space will be provided to give access to the interior of the gin.

7. In a machine for treating cotton designed to be positioned on top of a gin stand, in combination with a main housing inclosing, in part, the cotton treating mechanism, a pair of supporting members for the machine, a housing section forming a trash receptacle extending between and connecting said members and forming a continuation of said main housing, a rotatable trash remover mounted in and extending between said supporting members and adapted, in operation, to remove trash from said housing section, and means for detachably connecting said supporting members to said machine, whereby the same, together with the parts carried 85 thereby, may be removed from the machine to give access to the interior of the gin.
